UNITED STATES PATENT OFFICE

2,478,949

MINIATURE GOLF GAME

Ivan M. Snyder, Rockford, Ill.

Application November 20, 1944, Serial No. 564,243

6 Claims. (Cl. 273—87)

1

This invention relates to a new and improved miniature golf game designed to be played on a game board by children and adults.

I am aware that efforts have been made to provide miniature golf games, but most of these have been too complicated and have involved too much of an element of pure chance in their playing, and have not, therefore, sufficiently closely resembled the regular game of golf, which is to such a large extent a game of skill. It is, therefore, the principal object of my invention to provide a miniature golf game in which chance devices are employed only to the extent of determining the number of strokes or plays in which a player gets his ball onto a putting green, and to determine also whether he shall have a short or long putt, the game from that point on being entirely up to the skill of the player in actually putting the ball into the cup, using a miniature putter and a small steel or other relatively "dead" or non-resilient and non-bounding ball on the felt surface provided for the putting green.

The chance devices, in accordance with my invention, are also designed to cooperate with fairway strips laid out on the board in such a way that a player will encounter traps that will cost him strokes or plays, similarly as in the actual outdoor game, to lend further interest and more closely resemble the outdoor game, and these chance devices are further so designed to determine in the case of a long hole the number of strokes or plays used in wood shots before other chance devices are employed for the approach shots that ultimately determine in how many strokes the player gets his ball on the putting green, and determine also whether he has a long or a short putt.

Still another object is to provide in a game of the kind mentioned an auxiliary putting green with a suitably undulated surface, which may be placed over the flat putting surface otherwise used, whereby to lend "sportiness" to the game and require a higher degree of skill in its playing and further increase the interest among those players who are accustomed to playing the regulation game on sporty courses that usually have undulated greens.

The invention is illustrated in the accompanying drawings, in which—

Fig. 1 is a plan view of a game board made in accordance with my invention, showing the central putting green and the various fairway strips going to make up a nine hole course, together with the two sets of spinners provided for the woods shots and approach shots;

2

Fig. 2 is a plan view and side view of a player token used for designating the different players on the tees and fairways, the same being shown approximately full size;

Fig. 3 is a view of the steel ball used on the putting green, shown approximately full size;

Figs. 4 and 5 are a side view and end view of a miniature putter used with the steel ball on the putting green, shown approximately full size;

Fig. 6 is a plan view of the putting green portion of the game board on a larger scale, the green being shown approximately half the actual size in this view;

Fig. 7 is a plan view of one portion of the board showing on a larger scale one of the spinners for wood shots;

Fig. 8 is a plan view of another portion of the board showing a typical fairway strip requiring wood shots and approach shots;

Fig. 9 is a plan view of one portion of the board showing on a larger scale one of the spinners for approach shots;

Fig. 10 is a plan view of another portion of the board showing a typical fairway strip requiring only approach shots;

Fig. 11 is a section on the line 11—11 of Fig. 6, but illustrating an auxiliary putting green with a suitably undulated surface superimposed on the flat surface of the other green, and

Fig. 12 is a plan view of the undulated green illustrating three 120° segments each having a different conformation, and showing the markings at which the player is required to "spot" the ball in putting for the different holes on long and short puts.

The same reference numerals are applied to corresponding parts throughout the views.

Referring first to Fig. 1, the reference numeral 13 designates a flat game board, which preferably though not necessarily has an upstanding marginal frame 14, with a view to retaining the steel ball 15 (Fig. 3), in the event the ball is accidentally struck too hard with the putter 16 (Figs. 4 and 5), by an inexperienced player, or in the event the board is accidentally tilted. Nine fairway strips are suitably marked off on the board 13, as indicated at 17 to 25, seven of these being for holes requiring wood shots, as well as iron shots, but the other two holes, Nos. 2 and 6, the strips for which are numbered 18 and 22, being short holes requiring only iron shots. All of the wood shots are made using the spinners 26, which cooperate with circular charts 27 marked "Drive and brassie," and all iron shots are made using the spinners 28 which cooperate with circular charts 29.

labeled "Approach." The fairway strips 17 to 25 each include a tee portion 30 on one end and a green portion 31 on the other end, but the putting, as will soon appear, is done on a large circular putting green 32 provided on the central portion of the board, this one green being common to all nine holes and including a center hole, or cup, 33 of a size bearing, of course, the proper relationship to the size of the steel ball 15 used for putting. I prefer to have the ball 15 larger in diameter than the hole 33 so that it can be putted more easily and can be picked up easily when it is in the hole. The fairway strips 17 to 25 also include areas marked "Traps," as indicated at 34, and these cooperate with segments 35 in the charts 21 marked "Trap," and a player using a spinner 26 for a wood shot and having it stop at the segment 35 marked "Trap" will advance his player token 36 (Fig. 2) to the nearest trap in a forward direction from wherever his token may be set at the time, whether it be on a tee 30 or on one of the various sections 31 marked "Brassie." The approach charts 29 also include segments 38 marked "Trap." In fact, there are two such segments in each of these charts as compared with only one such segment 35 in the charts 21 for wood shots, on the theory that the greens are usually trapped even where the fairways are more or less clear of such hazards, and a player in making an approach shot toward the green is more apt to land in a trap than he is when making a wood shot. A player using a spinner 28 will in the event it stops on a segment 38 marked "Trap" advance his player token 36 to the nearest trap, whether he be on the tee for the second and sixth holes at the time or in any one of the fairway sections 39 marked "Approach." The fairway sections 37 and 39 are marked off for 50-yard intervals, a 400-yard hole, like hole No. 8, having seven of these sections in addition to the tee portion 30, and the green portion 31 being counted as the last fifty yards, a 200-yard hole, like hole No. 2, having three sections 39 in addition to the green section 31, and so on for the various holes. Chance determines only the number of strokes or plays required for a player to advance his player token 36 onto the green 31, and at that point the player is required to exercise skill in holing out, using the steel ball 15 and putter 16 for the putts. In that way this game bears a much closer resemblance to the outdoor game of golf, wherein it has become a common slogan to "drive for show and putt for dough"—meaning that the decision is left to putting. Invariably most championships are determined just that way in the actual outdoor game. The putting green 32 is preferably a disk of green felt, or billiard cloth, having a circular strip 40 marked off near its outer margin labeled "Long putt" and another concentric circular strip 41 marked off at about half the radial distance from the hole 33 labeled "Short putt." This is for the purpose of determining where the player shall spot his steel ball 15 for putting. The approach charts 29 have segments 42 labeled "On long putt" and other segments 43 labeled "On short putt," but there are eleven of the long putt segments 42 as compared with only two short putt segments 43, on the theory that the average golfer leaves himself a fairly long putt in approaching most greens in about that ratio as compared to the number of times he approaches close to the hole. From the standpoint of the present game, a long putt is considered one in which the player possessing a fair degree of skill should be able to hole out in

two putts, and a short putt is one which a player of the same skill should be able to hole out in one putt. Of course, a player who develops a good putting stroke using the miniature putter 16 will occasionally hole out a long putt in one putt, and there again he can, as he is accustomed to doing in the outdoor game, make up by good putting for what he might term "tough luck" out on the fairway, and whereas he should have gotten on the green in the regulation two strokes on a 4-par hole and holed out in two more strokes for a par-4, it is possible with the present combination to get a par-4 even though he has taken three strokes to reach the green and has left himself a long putt. It is apparent, therefore, to what a close extent the present game resembles the outdoor game and to what a close extent the element of skill present in the outdoor game has been carried into this game, to lend interest for young and old alike.

There is one segment 44 on each of the approach charts 29 marked "Hole out," and a player using a spinner 28 for his approach shot and having it stop on this segment 44 is considered to have holed out his approach shot. This segment 44 should not be of as large included angle as the other segments in these charts, but has been so illustrated only for better illustration and for easier lettering. These segments should be in the range of from one-quarter to one-half the included angle of any one of the other segments, in order thereby to correspondingly reduce the chances of a player holing out and accordingly more closely resemble the player's chances in the outdoor game in that respect.

In playing the game, one, two, or more players can play at a time, the same as in the outdoor game of golf. If there are four playing, as in a foursome, each player will use a player token 36, and these may be colored differently in order to distinguish the players on the tees and along the fairway strips. In starting the game, having suitably determined the order in which the players will drive off the first tee, the first player spins a spinner 26 for his wood shot. If the spinner stops on the segment 45 marked 100-yards, or 200-yards, or 250-yards, he will place his player token 36 on the section 37, or 39, for the yardage indicated. Thus for hole No. 1 anything up to 150-yards leaves that player in a fairway section 37 marked "Brassie," so that his next shot must be played using the same spinner 26 for a wood shot. If he gets 200 yards or 250 yards on his first spin or shot, he places his player token 36 on the appropriate fairway section for the yardage indicated, and these sections are marked "Approach," and in such an event that player for his second shot uses one of the spinners 28 for an approach. If the spinner stops on the 150-yard indication, this would necessitate the player using the wood shot spinner 26 again for his next shot, and should he on his next shot get 250 yards, this would mean a total of 400 yards for the two shots, placing the player token 36 on the green 31 at the end of the fairway strip. In that event the player is considered as having landed on the green, and will place his steel ball on the green 32 for a long putt, without using the approach spinner 28. After the first player has taken his shot, the other players take their shots in the order agreed upon, and thereafter the shots will be taken in the order determined by the location of the player tokens on the fairway strips, similarly as is the custom in the play along a fairway in the outdoor

game of golf, the player farthest from the green shooting first, and so on. Each player, of course, keeps track of his own strokes, counting one stroke per spin of the spinner 26 or 28 and, of course, one stroke for each stroke of the putter 16. A player in teeing off for hole No. 1 may have the spinner 26 stop on the segment 48 marked "Top 50," which indicates a topped tee shot going only 50 yards, and that player will accordingly place his token 36 in the first fairway section 31 marked 10 for that yardage. If, on the other hand, the player in teeing off on hole No. 1 has the spinner 26 stop in the segment 35 marked "Trap," he will place his token 36 in the second fairway section 37, which is the first one bearing a "Trap" designation, as indicated at 34. The player having that happen may have the misfortune to have the spinner stop at the same segment 35 on the next shot, in which event he will advance to the next fairway section 37, where another "Trap" 34 has been indicated. It is possible, therefore, for a "duffer" to use three strokes in moving his token 36 only three fairway sections 31 from the tee. On the other hand, a player having the good fortune to land on the 200-yard or 250-yard fairway section in teeing off may still encounter a trap 34 on his approach shot when he uses the approach spinner 28, there being two "trap" segments 38 in the chart 29. It is, further, entirely possible for such a player to use two, or even three, strokes in getting out of the trap, because the spinner 28 may conceivably stop again on a "trap" segment on the next succeeding spin or spins. In that way the element of chance, which is, of course, present in the outdoor game of golf, has been retained in this game to the correct percentage, so that on a par-4 hole, like hole No. 1, a player will only occasionally land on the green in two strokes and then will usually have a long putt left, which will usually require two, or even three, strokes to hole out. The element of skill, which is present to such a large extent in the putting in the outdoor game, has, therefore, been retained in this game to make it more interesting for everyone playing it. Assuming the four players have completed the first hole with two par-4's and two bogie-5's, the two players having pars will shoot first off the No. 2 tee, and the two players having 5's will shoot next. The second hole being an approach hole, the approach spinners 28 are used for the tee shots. Here again the possibility of landing in a trap, like that indicated at 34, is present, and one or two of the four players is apt to have that occur while the others land on the green for long or short putts, as the case may be, depending, of course, on where the spinner 28 stops. It is entirely possible, but highly improbable, that the spinner 28 will stop on the segment 44 (especially when reduced in size as contemplated) for a hole-in-one. The game is scored in the same way as the outdoor game of golf. If par for the course is thirty-six, the average player will find it taxes his skill to the utmost to make that score, and he is frequently called upon to hole out long putts to make up for "trouble" on the fairways. The average player will usually score in the forties, and a close resemblance to the scoring in the outdoor game is found will prevail.

Where the players desire to make the game more difficult, an undulated green, like that indicated at 41, may be provided, this being in the form of a disk 48 that may be superimposed on the green 32. A ferrule 49 having the same inside diameter in its upper portion as the hole 33 and the same outside diameter in its lower portion

as said hole is inserted with a press-fit in a center hole 50 in the disk 48, and is adapted to be entered with a close fit in the hole 33, so as to hold the disk 48 against accidental displacement after it has been placed on the green 32 for use of the undulated green 41. The construction also permits the disk 48 to be turned, so that it will be convenient for a player stationed at one corner of the board 13 to putt from any designated portion of the green 41. The green 41 may be marked off into three 120° segments, as indicated diagrammatically in Fig. 12, each segment having a different contour, to give the ball a roll to the right or left, or up or down in a radial direction, with respect to the hole 49. If desired, "spots" may be designated, as indicated at 51, in these three 120° segments, where a player must place his ball 15 in putting for the different holes in the nine hole course. In that way, all players have the same difficulties on a long putt for a given hole and all have the same difficulties for a short putt on a given hole, the long putts being designated by a circular strip 40 and the short putts by a concentric circular strip 41, similarly as on the green 32. In that way the green can be made to require a much greater degree of skill in putting, to the same extent that the undulated greens on a sporty outdoor golf course require greater skill than do the flat greens on many municipal courses.

It is believed the foregoing description conveys a good understanding of the objects and advantages of my invention. While I have shown spinners for the chance devices it will, of course be understood that any other form of chance devices, such as dice or cards, might be used, if desired. The appended claims have been drawn to cover all legitimate modifications and adaptations.

I claim:

1. A table-type miniature golf game apparatus playable by a combination of chance and skill comprising in combination a board providing a playing surface having thereon the representation of a plurality of miniature sized golf holes, each specifically different in layout and each including tees, fairways and hazards over which and to a specific point on a green a play piece of each contestant and representative of a golf ball is advanced by chance means, a single putting surface constituting the aforesaid green and being common to all of the plurality of golf holes and being of enlarged dimensions relative to the width of any of the fairways of said holes and of an area representing a large fraction of the whole area of the playing surface of the board, and said green being provided with a hole to receive a miniature ball rolled on and over said green and into said hole.
2. A table-type miniature golf game apparatus playable by a combination of chance and skill comprising in combination, a board providing a playing surface having thereon the representation of a plurality of miniature sized golf holes, each specifically different in layout and each including tees, fairways and hazards over which and to a specific point on a green a play piece of each contestant and representative of a golf ball is advanced by chance means, a single putting surface constituting the aforesaid green and being common to all of the plurality of golf holes and being of enlarged dimensions relative to the width of any of the fairways of said holes and of an area representing a large fraction of the whole area of the playing surface of the board, said

green being provided with a hole to receive a miniature ball rolled on and over said green and into said hole, the surface of said green being provided with undulations whereby a ball may smoothly roll over the same yet making the passage of the ball over the green and into the hole more difficult of attainment.

3. A table-type miniature golf game apparatus playable by a combination of chance and skill comprising in combination, a board providing a playing surface having thereon the representation of a plurality of miniature sized golf holes each specifically different in layout and each including tees, fairways, and hazards over which and to a specific point on a green a play piece of each contestant and representative of a golf ball is advanced by chance means, a single putting surface constituting the aforesaid green and being common to all of the plurality of golf holes and being of enlarged dimensions relative to the width of any of the fairways of said holes and of an area representing a large fraction of the whole area of the playing surface of the board, said green being provided with a hole to receive a miniature ball rolled on and over said green and into said hole, said green being provided on its surface with undulations, and the green being divided into segments the surface contours of which differ in respect to one another.

4. A table-type miniature golf game apparatus playable by a combination of chance and skill comprising in combination, a board providing a playing surface having thereon the representation of a plurality of miniature sized golf holes each specifically different in layout and each including tees, fairways, and hazards over which and to a specific point on a green a play piece of each contestant and representative of a golf ball is advanced by chance means, a single putting surface constituting the aforesaid green and being common to all of the plurality of golf holes and being of enlarged dimensions relative to the width of any of the fairways of said holes and of an area representing a large fraction of the whole area of the playing surface of the board, said green being provided with a hole to receive a miniature ball rolled on and over said green and into said hole, said green being provided in its surface with undulations, said green being divided into segments the surface contours of which differ in respect to one another, and said green being mounted on the board for rotation in a horizontal plane to permit presentation of the same green contour to a contestant irrespective of the contestant's location about the board.

5. A table-type miniature golf game apparatus playable by a combination of chance and skill comprising in combination, a board providing a playing surface having thereon the representation of a plurality of miniature sized golf tees, fairways, and hazards over which and to a specific point on a green a play piece of each contestant and representative of a golf ball is advanced by chance means, a single putting surface constituting the aforesaid green and being com-

mon to all of the plurality of golf holes and being of enlarged dimensions relative to the width of any of the fairways of said holes and of an area representing a large fraction of the whole area of the playing surface of the board, said green being provided with a hole to receive a miniature ball rolled on and over said green and into said hole, the surface of said green having a plurality of segments each provided with an undulating surface, the surface contours of said segments differing in respect to one another, indicia on each segment for indicating the position from which a ball is to be rolled over the green and into the hole, and said green being mounted on the board for rotation in a horizontal plane to permit the positioning of any of said indicia to a contestant irrespective of the position of the contestant about the board.

6. A table-type miniature golf game apparatus playable by a combination of chance and skill comprising in combination, a board providing a playing surface having thereon the representation of a plurality of miniature sized golf holes each specifically different in layout and each including tees, fairways and hazards over which and to a specific point on a green a play piece of each contestant and representative of a golf ball is advanced by chance means, a single putting surface constituting the aforesaid green and being common to all of the plurality of golf holes and being of enlarged dimensions relative to the width of any of the fairways of said holes and of an area representing a large fraction of the whole area of the playing surface of the board, said green being provided with a hole to receive a miniature ball rolled on and over said green and into said hole, and said green being marked with concentric circles struck with the hole as the center and indicating the placements of the miniature ball for short and longer distances the ball must be rolled into the hole by any contestant irrespective of the position of the contestant about the board.
